(57) **CLAIM**

The ornamental design for a headset virtual reality hardware device, as shown and described.

DESCRIPTION

FIG. 1 is a front perspective view of a headset virtual reality hardware device showing our new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The greyscale surface shading shown in FIGS. 1-7 is provided solely for the purpose of illustrating surface contours. The differing shades of greyscale shown in FIGS. 1-7 form no part of the claimed design. The broken line showing of portions of the headset in FIG. 3 and the white areas located within the broken lines are for the purpose of illustrating environmental structure and forms no part of the claimed design.
